UNITED STATES PATENT OFFICE.

LOUIS CLÉMENCET, OF WEST HOBOKEN, NEW JERSEY, ASSIGNOR TO HENRY M. BIRGE, OF BUFFALO, NEW YORK.

DESIGN FOR WALL-PAPER.

SPECIFICATION forming part of Design No. 26,121, dated September 29, 1896.

Application filed August 24, 1896. Serial No. 603,780. Term of patent 3½ years.

To all whom it may concern:

Be it known that I, LOUIS CLÉMENCET, a citizen of the United States, residing at West Hoboken, in the State of New Jersey, have 5 invented and produced a new and original Design for Wall-Paper, of which the following is a specification, reference being had to the accompanying drawing, showing a part thereof.

10 The design consists of an arrangement of groups of flowers and leaves and musical instruments, with festoons of flowers and leaves connecting said groups by bows of ribbons, as represented in the accompanying drawing.

15 The border for the said design is also formed of groups of flowers and leaves and musical instruments, with festoons of flowers and leaves connecting said groups by bows of ribbon and attached to ornamental scrolls above said groups and ornamental scrolls below said 20 groups, as shown in the drawing.

What I claim is—

The design for wall-paper herein shown and described.

Witness my hand this 21st day of August, 25 1896.

LOUIS CLÉMENCET.
